Assistant Examiner — Yen Le Southwood

CLAIM

The ornamental design for an x-shape steaming rack, as shown and described.

DESCRIPTION

FIG. 1 is a perspective view of an x-shape steaming rack in an assembled state showing my new design;
FIG. 2 is a front view in an assembled state thereof;
FIG. 3 is a back view in an assembled state thereof;
FIG. 4 is a left view in an assembled state thereof;
FIG. 5 is a right view in an assembled state thereof;
FIG. 6 is a top view in an assembled state thereof;
FIG. 7 is a bottom view in an assembled state thereof;
FIG. 8 is a perspective view of the x-shape steaming rack in a disassembled state thereof;
FIG. 9 is a front view in a disassembled state thereof;
FIG. 10 is a back view in a disassembled state thereof;
FIG. 11 is a left view in a disassembled state thereof;
FIG. 12 is a right view in a disassembled state thereof;
FIG. 13 is a top view in a disassembled state thereof; and,
FIG. 14 is a bottom view in a disassembled state thereof.
